Fig. 2

FIGURE 1 is a perspective view of a combined holder and charging unit for electric toothbrush or the like, with the transparent cover assembled therewith, embodying my design;

FIGURE 2 is a perspective view of the same with the transparent cover removed to one side;

FIGURE 3 is a top plan view of the said charging unit, without the transparent cover; and

FIGURE 4 is a side view of the said charging unit, without the transparent cover, the other two sides being similar in appearance.

The bottom is substantially plain.

The power handle and toothbrushes shown in broken lines in FIGURE 1 are included for illustrative purposes only.

I claim:

The ornamental design for a combined holder and charging unit for electric toothbrush or the like, substantially as shown and described.
